UNITED STATES PATENT OFFICE.

IRVING B. WILLIAMS AND JAMES D. MCGILTON, OF TULSA, OKLAHOMA.

OIL-PUMP CONSTRUCTION.

Application filed October 14, 1926. Serial No. 141,521.

This invention relates to oil pump construction and refers more particularly to a construction by means of which the suction cups within the pump barrel of an oil pump are more effectively lubricated and the accumulation, or deposition of paraffin within the tubing and pump considerably retarded.

Among the salient objects of the invention are to provide an oil pump construction adapted to be used in the pumping of oil wells, in which, due to the arrangement of the elements, the oil pump is more effectively lubricated thereby materially lengthening the life of the pump mechanism and further the particular arrangement prevents deterioration caused by gas cutting or by improper lubrication when the well is "pumped off", the latter occurrence being experienced when the pump barrel becomes dry during intervals between pumping off the heads; to provide a pump construction which not only facilitates the lubrication of the pump mechanism, but retards and to a great extent prevents the accumulation of paraffin wax within the tubing and around the pump mechanism, and in general to provide a construction of the character herein-after referred to.

Fig. 1 is a side sectional view of an oil well with the pump and cup lubricator and de-paraffiner in position.

Fig. 2 is a sectional detail of the pump mechanism shown in Fig. 1.

Referring to the drawings, at 1 is shown a pump barrel, attached to the tubing 1^a. To the lower extremity of the pump barrel is attached a threaded nipple 2, preferably of about five inches in length, by means of a collar 2^b internally threaded to engage the pump barrel and the upper portion of the nipple. The lower end of the nipple is threaded both externally and internally. The external threading receives the collar 2^b, which also engages the upper end of the tubing 3. Into the internal thread of the nipple is screwed a length of three-quarter inch pipe 4, which is positioned internally of the outside two inch tubing, extending into a lower enlarged portion of the outside tubing. Just below the collar 2^b and below

the threaded connection between the inside three-quarter inch pipe and the internally threaded nipple 2 are a plurality of perforations 5, through which the oil passes from the outer casing 6 into the tubing. The 55 tubing 3 has connected to its lower extremity a portion of pipe 7, of enlarged diameter. The bottom of the lower end of this enlarged section of pipe is drawn down to substantially the diameter of the two inch pipe, 60 and to this lower end is connected an anchor 8, closing off the lower end of the tubing.

As suggested the three-quarter inch pipe connected into the nipple 2 extends into the 65 lower part of the enlarged portion of the two inch tubing, designated as 7. The lower extremity of the three-quarter inch pipe terminates in an open bell-shaped nipple 9, having a three-quarter inch connection to 70 the pipe and enlarging to an inch and one-quarter opening at its mouth. The size of this lower opening may vary according to the needs and operation of the pump, the maximum diameter being limited only by the 75 size of the enlarged portion of the pipe 10.

In the shell of the enlarged portion of the tubing and above the lower open end of the three-quarter inch pipe 4 is a 80 perforation 10. This hole or perforation has a critical size which depends primarily upon the delivering capacity of the oil sand. Normally the perforation will range from one-sixteenth of an inch to an inch in diameter. The upper perforations 5 in the two 85 inch tubing will normally range from one-quarter to one-half inch in diameter.

The suction cups 11, positioned in the pump barrel 1, are reciprocated by means of a pump rod 12, which is functioned from 90 the surface. At the bottom of the pump barrel is a standing or stationary valve 13, and above the suction cups and attached to the pump rod is a reciprocating or travelling valve 14, the details of the particular 95 pump mechanism forming no part of the present invention.

In operation the oil enters through the 100 perforations 5 and also the perforations 10 and fills the two inch tubing. When it is

desired to pump off the well the pump is started and the oil is drawn down through the two inch tubing into the bottom of the open ended three-quarter inch pipe, and 5 thence into the pump barrel. By means of this construction the pump is always assured of a dense liquid head relatively uncontaminated by gas, sand or other deleterious matter. The travel of the oil through 10 the perforations, thence downwardly through the tubing 3 into the flared mouth 9 of the pipe 4 and upwardly through the three-quarter inch pipe, prevents the pump becoming gas bound and to a great extent 15 eliminates the objectionable accumulation of paraffin in the valves and barrel of the pump on account of the mechanism being at all times immersed in liquid oil. Furthermore, due to the circuitous travel of the 20 oil on entering the pump barrel any sand will be settled out and substantially all of the gas separated from the oil as it passes through the upper perforations 5 in the outer tubing. It will also be appreciated 25 that the constricted upper passage between the inner and outer pipe will cause an increase in the rate of flow of the oil therethrough, which rate will be decreased in the lower expansion chamber, thus further insuring 30 the settling out of entrained sand. This improved separation arising from the initial increase in rate of flow of the oil and the subsequent decrease of the rate in the lower chamber is a very desirable and novel feature 35 of the present invention, and one which obviates the necessity of providing an involved and costly mechanism.

The perforation 10 serves more as an 40 equalizing hole, permitting a regulated inflow of oil during the pumping period, and assuring a solid head of liquid oil to the suction end of the pump at all times.

In actual operation the trouble and expense 45 in connection with oil well pumping has been materially diminished, primarily due to the decrease in cost of replacement for pump parts and in labor in removing the string of tubing, in order to clean the pump and valves of accumulated paraffin, which 50 renders the pump inoperative when the accumulation has become excessive.

Furthermore the assurance of a solid liquid 55 head during the pumping operation and also when the well has been pumped off at the suction end of the pump, prevents the admission of gas which carries with abrasive sand. The fact that there is at all times liquid oil in contact with the pump mechanism 60 reduces materially the excessive wear usually accompanying the operation of a pump in a dry pump barrel, and maintains the paraffin present in solution in suspension.

As the gas is trapped off by the existence 65 of the liquid in a three-quarter inch pipe, there is little or no difficulty encountered

with the drying of wax on the pump parts, due to the passage of dry free gas through the pump mechanism. The oil in the pump and three-quarter inch pipe prevents the formation of paraffin with its accompanying 70 inconveniences, difficulties and expense to the pump operation.

It will be appreciated that the particular positioning and arrangement of the parts may be varied without departing from the 75 spirit or scope of the invention.

We claim as our invention:

1. An oil well pump construction, comprising pump mechanism attached to a tubing including stationary and traveling valves 80 and valve cups, mounted upon a pump rod and positioned within a pump barrel, a tubing extension below the pump mechanism, comprising a narrow elongated upper portion and an expanded lower portion, perforations in the upper portion of the tube extension and a perforation near the lower portion thereof, a pipe within the tube extension and of smaller diameter having an open lower end, said pipe extending from the pump barrel and having communication therewith into the lower portion of the tube extension. 85

2. An oil well pump construction, comprising pump mechanism attached to the tubing, including stationary and traveling valves and suction elements, said traveling valves and suction elements mounted upon a pump rod, an elongated tube extension attached to the lower end of the pump barrel, 95 but blanked off from communication therewith, said tube extension having a section of increased diameter, and terminating in a closed end, a pipe having a lower open end positioned within the tube extension having 100 communication with the pump barrel, and terminating in the enlarged portion of the tube extension, said pipe defining a restricted passage with the upper portion of the tube and an expansion chamber with the lower 110 portion, perforations in the upper portion of the tubing below the pump barrel and a perforation in the enlarged portion of the tubing above the end of the inside pipe. 115

3. Oil well pump construction, comprising pump mechanism mounted on a pump barrel and attached to a tubing within an oil well casing, a tube extension below the barrel but blanked off from communication therewith, said tubing having a closed lower extremity and a section of enlarged cross sectional diameter, perforations in the upper portion of the tube extension below the pump mechanism and communication between the enlarged section of the tube extension and the casing, a pipe of smaller diameter than the tube extension positioned therein, and defining therewith an upper restricted passage adapted to increase the speed of flow of oil therethrough, and a 120 125 130

lower expansion chamber adapted to decrease the speed of flow of the oil, the upper extremity having communication with the pump barrel and the lower open end terminating in the enlarged portion of the tube extension.

4. A construction, such as that described

in claim 3, in which the communication between the enlarged portion of the tube extension and casing is positioned above the 10 lower extremity of the inner pipe terminating in said tube extension.
